Patented Aug. 31, 1920.

WITNESS:

Aug. Kahn,

INVENTOR.

BY Nathan H. Price

Victor J. Evans

ATTORNEY.

UNITED STATES PATENT OFFICE.

NATHAN H. PRICE, OF SHANNON, ALABAMA.

PIPE.

1,351,683.

Specification of Letters Patent. Patented Aug. 31, 1920.

Application filed August 25, 1919. Serial No. 319,598.

To all whom it may concern:

Be it known that I, NATHAN H. PRICE, a citizen of the United States, residing at Shannon, in the county of Jefferson and 5 State of Alabama, have invented new and useful Improvements in Pipes, of which the following is a specification.

This invention has reference to a smoker's pipe.

10 The primary object of the invention is to provide a pipe with means whereby the bowl and stem may be easily, quickly and effectively cleaned.

Other objects and advantages will present 15 themselves as the nature of the invention is better understood, reference being had to the accompanying drawings, in which:

Figure 1 is an elevation of the improvement.

20 Fig. 2 is an approximately central longitudinal sectional view through the same.

Fig. 3 is a similar sectional view illustrating the manner in which the entire pipe and stem and mouth piece are cleaned.

25 Fig. 4 is a partial sectional view showing the manner in which the ash is removed from the bowl.

Fig. 5 is a similar view showing the manner in which the pipe is supported for drying after being cleaned.

30 Fig. 6 is a view illustrating the application of the improvement to a rounded stem pipe.

Figs. 7 to 10 inclusive show modified 35 forms of a supporting clamp carried by the pipe stem.

In the drawing the numeral 7 designates 40 a pipe of the ordinary construction. The bowl 8 at its lower and closed portion is provided with a central aperture 9, the bore of the stem 10 of the said pipe being disposed a slight but suitable distance above the lower wall of the bowl. On the stem 10 is screwed the usual mouth piece 11. Secured to the 45 outer end of the stem 10 is a clamp. This clamp is preferably constructed from a single strand of wire having one of its ends offset and let into a depression in the under face of the stem and from thence wound

50 around the stem as at 13 and the free end thereof is bent upon itself to provide a hook 14 that is disposed centrally of and on the under face of the stem. Between the aperture 9 in the bowl and the clamp, the stem 55 is approximately centrally formed with a depression or pocket 15.

Designed to be received in the bowl is a disk-shaped cleaning member 16. The under face of this member is preferably shaped to correspond with the lower wall of the bore of the pipe bowl, and the said lower wall has centrally projecting therefrom a stem 17. This stem has its outer end slotted and pivotally secured in the slot is the eye portion of a resilient rod 18. The rod, when 60 the disk-shaped cleaning member is in normal position in the bowl is designed to be received by the hook member of the catch, and being constructed of resilient material is slightly bent or rounded so as to contact 65 with the under face of the stem and with the hook. In this manner the rod exerts a spring influence on the stem of the cleaning disk so as to effectively hold the same in the bottom of the bore or smoke chamber 70 of the bowl. It will be apparent that when the bendable spring rod member is brought in a line with the stem of the cleaning disk 16, the said disk may be forced outward of the smoke chamber or bore of the bowl removing the tobacco therefrom as well as the 75 moisture caused from the tobacco. The disk member is designed to be employed as a plunger, in which instance the pipe is submerged in water and a reciprocatory movement is imparted to the disk when the latter is arranged in the smoke chamber or bore of the bowl. When the pipe is thus cleaned one finger of the operator is arranged 80 against the aperture 9 to close the said aperture. When the pipe has thus been cleaned the disk is removed from the bowl and held in inverted position so that the conical-shaped end of the stem is received in the depression or pocket. The rod 18 is then 85 arranged in the hooked end of the clamp and the outer end thereof exerts a spring pressure between the stem of the cleaning member, the hook of the clamp and the mouth piece of the pipe where is a small 90 slot to hold the end of the rod, retaining the said pipe at a slight inclination but forming a rest therefor so that the same may be readily drained and dried.

As my improvement is applicable to 95 curved or rounded stem pipes as well as to straight stem pipes, I have, in Fig. 7 of the drawings shown the application thereof to such construction of pipes, the elements constituting my improvement being precisely 100 similar to that previously described, and therefore the reference characters indicating

the several parts in the figures previously described may be considered as equally applicable to the construction illustrated in the said Fig. 7. It is to be understood that while the rod 18 is of spring material the same may be readily bent and will thus readily conform itself to the shape of the rounded pipe stem shown in the said Fig. 7.

Having thus described the invention, what is claimed as new, is:—

1. In combination with a smoker's pipe, of cleaning means therefor including a disk received in the smoke chamber of the pipe bowl and normally seated below the passage in the stem of the pipe, said disk having a stem passing through an opening in the bottom of the bowl, a flexible spring rod pivotally secured to the outer end of the stem, and means on the stem of the pipe for supporting the said rod.

2. In combination with a smoker's pipe having an opening through the bottom of the smoke chamber thereof, a clamp having a

hook-shaped end on the stem of the pipe, and the said stem between the clamp and the referred to opening having a depression providing a pocket on its under face, of a combined cleaning and supporting means for said pipe including a disk designed to be received in the smoke bowl below the passage in the stem of the pipe, a stem on said disk passing through the opening in the smoke bowl, a spring rod pivotally secured to the outer end of the stem designed to contact with the stem of the pipe and to be engaged in the hook of the clamp for holding the said disk in the smoke chamber, and the stem of the said disk designed to be received in the opening in the stem of the pipe and the spring rod adapted to exert a pressure between the hook of the clamp and the mouth piece of the pipe when the device is employed as a support for the pipe.

In testimony whereof I affix my signature.

NATHAN H. PRICE.
